CLAIM

The ornamental design for a cocktail smoker, as shown and described.

DESCRIPTION

FIG. 1 is a front and top perspective view of a cocktail smoker, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front and top exploded perspective view of the cocktail smoker; and,

FIG. 10 is a cross-sectional view thereof, taken along 10-10 of FIG. 9.

The broken lines in the figures depict portions of the cocktail smoker that form no part of the claimed design.
